UNITED STATES PATENT OFFICE

GEORGE HALL WHITE, OF WASHINGTON, DISTRICT OF COLUMBIA

CONDENSER

Application filed June 12, 1929. Serial No. 370,314.

This invention relates to an improvement in condensers designed more particularly for the condensation of ammonia gas used in a refrigerating cycle where the ammonia is

5 the refrigerating agent.

The improved condenser is directed more particularly to a means for forcing a body of air over the surface of a body of water to extract heat from the latter on the principle 10 of evaporation; a particular detail of the improvement residing in the provision of means whereby the water surface affected by the air is of extremely large surface proportions notwithstanding the fact that the 15 condenser as a whole is comparatively small and compact. This particular detail resides in the provision of means whereby the water body is divided into a comparatively large number of film-like areas, each segregated 20 from the others and each presenting a hollow space within the film through which the air is forced under pressure for evaporation purposes.

A further object of the invention is the 25 provision of means whereby the air in its initial delivery to the condenser is directed into contact with the water to assist in cooling the same by evaporation.

A further object of the present invention 30 is in the provision of means for utilizing the water films for extracting heat from tube-like structures and in directing the gas to be condensed into a more or less circuitous path lengthwise the condenser and in intimate 35 contact with the exterior of the metallic tubes, whereby the ammonia enters the condenser at one end as a gas and is delivered at the opposite end as a liquid.

A further object of the invention is the 40 provision of means whereby the air under pressure is initially directed through a somewhat elongated passage and during this travel is subjected to the cooling influence of the water of the condenser both by contact 45 of such water with the casing forming the passage and also through the fact that the casing is in part perforated to permit the entrance of some of the water directly into the passage, whereby the air, when reaching the tubes, is appreciably cooled for a more

effective heat exchange with the film of water flowing down the interior of the tube.

The invention is illustrated in the accompanying drawings, in which:

Figure 1 is a view in elevation, partly in 55 section, showing the improved condenser.

Figure 2 is a plan view of the same.

Figure 3 is an enlarged broken vertical section partly in elevation.

The improved condenser comprises a cylindrical casing 1 of appropriate vertical and horizontal dimensions and provided inwardly of its respective open ends 2 and 3 with transverse plates 4 and 5 constituting headers, the arrangement of the headers relative 60 to the casing defining a space 6 above the upper header 4 and a space 7 below the lower header 5.

The casing 1, which may be mounted upon appropriate supports 8, is in open communication at the lower end with a housing 9 closed at the bottom and preferably of greater diameter than that of the casing, the upper margin of the housing wall being inwardly inclined at 10 for sealing connection with 70 the lower end of the casing 1.

The respective upper and lower chambers 6 and 7 of the condenser proper are in communication through a plurality of tubes 11. These tubes are supported by and open 75 through the lower header 5, and extend a slight distance above the upper header 4, as indicated in Figure 1. The tubes may be in any desired number and are preferably arranged rather close together throughout 80 the permissible area, it being understood of course that the tubes are wholly free of contact one with the other.

The upper end of each tube 11 is provided 85 with a deflector 12 in the form of a tubular member of a diameter somewhat less than that of the tube 11 and arranged within the latter. The deflector tube 12 has its lower edge out-turned at 13 to provide a means for securing the deflector tube in spaced concentric relation to and within the upper end of the tube 11. The out-turned flange 13 is perforated and the deflector tube 12 extends an appreciable distance above the upper open 90 end of the tube 11.

It will be understood that, as will be hereinafter explained, water is delivered to the upper chamber 6 in appreciable quantities to maintain a substantially constant depth at a point somewhat above the upper open end 5 of the tube 11 but below the upper open end of the deflector tube 12. Water will thus enter each tube 11 and be compelled to flow lengthwise said tube in the form of a thin 10 film of water which adheres to and covers the interior surface of the tube. The deflector tube 12 compels the entering water to form itself into a thin film, as will be apparent from the construction, and as a result 15 of this formation, that portion of the tube 11 inwardly of the film of water on the inner surface of the tube constitutes a free, uninterrupted passage having an inlet at the bottom of the tube and an outlet through 20 the deflector tube 12.

Arranged within the housing 9 is a conduit 14, the upper wall of which is perforated with comparatively small openings. The inlet or lower end of this conduit extends beyond the 25 casing 9 and is in open communication with a blower or fan which is appropriately driven to force air under pressure through the conduit. The upper or outlet end of the conduit 14 terminates below the chamber 7 of 30 the casing 1, so that at this point the conduit delivers air under pressure to the chamber 7 to permit said air under pressure to travel lengthwise the respective tubes 11 within 35 in the film of water flowing downwardly therein and in contact with such water film to thereby, under the well known principle of evaporation, provide for a heat exchange with the effect to materially cool the water column.

40 As stated, the conduit 14 is perforated on its upper surface and such conduit is arranged within the housing 9 to provide a water receiving chamber 16 below the conduit. The water gravitating through the tubes and 45 chamber 7 passes over and in contact with the conduit 14, an appreciable quantity of such water finding its way through the perforations in the conduit to be picked up by the air stream. This permits the air to initially 50 act on the water at this point to assist in cooling the same by evaporation.

In order to maintain a constant circulation of the water, that is a constant passage 55 of the same through the condenser during the use of the latter, a pump 17 has its inlet in communication with the chamber 16 and its outlet, by means of a pipe 18, in communication with a water delivery ring 19 which is arranged in the upper chamber 6 of the condenser. In order to avoid the water, when 60 delivered by the pump to the chamber 6, from reaching the interior of the deflector tube 12, the ring 19 is perforated on its outer circumferential area, as at 20, so that the 65 incoming water is directed in a series of

streams against the interior of the upper portion of the casing 1, so that it reaches the upper ends of the tubes 11 in a more or less quiescent state, and splashing or turbulence of the water, which might tend to permit the 70 same to enter the deflector tube 12, is entirely avoided.

The space within the casing 1 exteriorly of the tubes 11 and between the upper and lower headers 4 and 5 is open to the passage of the 75 medium to be condensed. Where the condenser is used for the condensation of ammonia gas, such gas is admitted through an inlet 21 at the upper end of the casing and the condensed ammonia delivered from the 80 condenser through an outlet 22, the latter of course being of less sectional area than the inlet. Immediately adjacent the inlet 21 and within the casing 1 is arranged a deflector plate 23 which causes the incoming gas to be 85 directed in a circuitous path with respect to the tubes 11. Thus, the gas is compelled to travel a comparatively long distance and is thereby brought into intimate contact repeatedly with the various tubes 11. 90

It will be noted that the heat exchange between the water and gas is through the tubes as an interposed medium and such tubes may be of high heat conductivity and comparatively thin. The heat exchange is thus 95 extremely effective, for the water and gas are separated only by the relatively thin walls of the tube and the extremely thin film of water avoids the difficulty of a solid column of water which is under the known objections 100 that the liquid at the center of the column is ordinarily insufficiently cooled and usually acts to prevent proper heat exchange.

With the improved condenser, the water 105 flows down the interior of the tubes as a thin film, is itself cooled by evaporation incident to the passage of a current of air under pressure within and throughout the length of such film, and when so cooled provides an effective heat exchange medium with the surrounding gas. The cooling and moistening 110 of the air delivered under pressure materially increases the evaporative or heat exchange effect of the air and this is a constantly recurring incident of the condenser of the present 115 invention.

Furthermore, the possibility of providing a large number of heat exchange units in a comparatively small space provides a factor 120 which, in the saving of space and relatively low first cost, is of extreme importance. The water, during its heat exchange function, flows entirely by gravity, avoiding the necessity of a pressure system and thereby 125 further reducing the cost and maintenance of the condenser.

What is claimed to be new is:

1. A condenser including a casing, an upper header defining an upper chamber at 130 one end of the casing, a lower header for

the casing defining a chamber at the lower end of the casing, tubes extending from and opening through the respective headers, said tubes being projected above the upper header, a deflector tube fitted within the projecting end of each of said tubes, said deflector tube being supported in concentric spaced relation with its tube and extending above the upper end of the tube to thereby cause the entering fluid to form as a film on the interior of the tube, a housing arranged below the lower chamber and in open communication therewith, and an air pressure conduit arranged in said housing, said conduit being formed with a series of minute openings to permit the air to be delivered therefrom in a series of independent streams. 2. A condenser including a casing, an upper header defining an upper chamber at one end of the casing, a lower header for the casing defining a chamber at the lower end of the casing, main tubes extending from and opening through the respective headers, said main tubes being projected above the upper header, a deflector tube fitted within the projecting end of each of said main tubes, said deflector tube being supported in concentric spaced relation with its main tube and extending above the upper end of the main tube to thereby cause the entering fluid to form as a film on the interior of the main tube, a housing arranged below the lower chamber and in open communication therewith, and an air pressure conduit arranged in said housing and in open communication with the lower chamber, the upper wall of said conduit being perforated. 3. A condenser including a casing, an upper header defining an upper chamber at one end of the casing, a lower header for the casing defining a chamber at the lower end of the casing, main tubes extending from and opening through the respective headers, said main tubes being projected above the upper header, a deflector tube fitted within the projecting end of each of said main tubes, said deflector tube being supported in concentric spaced relation with its main tube and extending above the upper end of the main tube to thereby cause the entering fluid to form as a film on the interior of the main tube, a housing arranged below the lower chamber and in open communication therewith, and an air pressure conduit arranged in said housing and in open communication with the lower chamber, said conduit having its upper wall formed to deliver air under pressure into said housing in a series of upwardly-directed streams. 4. A condenser including a casing, an upper header defining an upper chamber at one end of the casing, a lower header for the casing defining a chamber at the lower end of the casing, tubes extending from and opening through the respective headers, said tubes being projected above the upper header, a deflector tube fitted within the projecting end of each of said tubes, said deflector tube being supported in concentric spaced relation with its tube and extending above the upper end of the tube to thereby cause the entering fluid to form as a film on the interior of the tube, a housing arranged below the lower chamber and in open communication therewith, an air pressure conduit arranged in said housing and in open communication with the lower chamber, said conduit having its upper wall perforated, a water collection chamber in the housing below the conduit, means for circulating the water from the water collection chamber to the upper chamber of the casing, and means in the upper chamber of the casing to deliver the entering water against the wall of the chamber to avoid turbulence and splashing. 5. A condenser including a casing, an upper header defining an upper chamber at one end of the casing, a lower header for the casing defining a chamber at the lower end of the casing, tubes extending from and opening through the respective headers, said tubes being projected above the upper header, a deflector tube fitted within the projecting end of each of said tubes, said deflector tube being supported in concentric spaced relation with its tube and extending above the upper end of the tube to thereby cause the entering fluid to form as a film on the interior of the tube, a housing arranged below the lower chamber and in open communication therewith, an air pressure conduit arranged in said housing and in open communication with the lower chamber, said conduit having its upper wall perforated, a water collection chamber in the housing below the conduit, means for circulating the water from the water collection chamber to the upper chamber of the casing, and a ring in the upper chamber of the casing disposed adjacent the wall of such chamber and formed with perforations to direct the incoming water against the wall of the chamber. In testimony whereof I affix my signature. GEORGE HALL WHITE. [L. s.]
